Attorney

UNITED STATES PATENT OFFICE

ERNEST F. POHL, OF ST. LOUIS, MISSOURI, ASSIGNOR TO AUTOMATIC FIRE EXTINGUISHER AND ALARM CORPORATION, OF ST. LOUIS, MISSOURI

COMBINED FIRE EXTINGUISHER AND ALARM

Application filed June 26, 1930. Serial No. 464,081.

The invention relates to a combined automatic fire extinguisher and alarm.

The object of the present invention is to provide a simple, practical and efficient automatic fire extinguisher and alarm of strong, durable and comparatively inexpensive construction adapted to be readily installed in a house or other place and equipped with a fusible member adapted in the event of a fire to be fused by the heat thereof for releasing of a spring member capable when released of firing a dynamite cap and of breaking a hermetically sealed glass container containing a fire extinguishing liquid such as carbon tetrachloride.

With these and other objects in view, the invention consists in the construction and novel combination and arrangement of parts hereinafter described, illustrated in the accompanying drawings, and set forth in the claims hereto appended, it being understood that various changes in the form, proportion and minor details of construction, within the scope of the claims, may be resorted to without departing from the spirit of the invention or sacrificing any of the advantages thereof.

In the drawings:

Figure 1 is a side elevation of an automatic fire extinguisher and alarm constructed in accordance with this invention.

Fig. 2 is a perspective view of the same, the hermetically sealed glass container being removed.

Fig. 3 is a detail horizontal sectional view taken substantially on the line 3—3 of Fig. 1.

In the accompanying drawings, in which is illustrated the preferred embodiment of the invention, the automatic fire extinguisher and alarm comprises in its construction a bracket 1 constructed of heavy sheet metal or other suitable material consisting of a vertical body portion provided at its upper and lower ends with horizontal arms 2 and 3 having openings 4 and 5 for the reception of the end portions of a hermetically sealed glass container 6 designed to contain carbon tetrachloride or other suitable fire extinguishing liquid which is designed to be converted into a gas by the heat of the fire and to smother or extinguish the same in the usual manner.

The upper and lower ends of the glass container extend into the openings of the arms 2 and 3 which are sufficiently resilient to enable the container to be readily placed in position, and the metal is sufficiently strong to firmly support the container in an upright position as clearly illustrated in Fig. 1 of the drawings.

The body portion of the bracket is provided with perforations 7 for the reception of screws or other suitable fastening devices for securing the bracket to a wall or other suitable support, and the bracket is equipped at the back with a resilient arm 8 of relatively light spring metal connected at its lower end 9 to the bracket and provided at its upper end with a head 10 of substantially cylindrical form. The spring 9, which forms a hinge member, extends longitudinally of the bracket and is located at the lower portion thereof. The head 10 has a pointed end 11 which is maintained in contact with the adjacent portion of the hermetically sealed glass container by the resiliency of the lower arm or spring 8. The head 10 projects rearwardly from the arm or spring 8 to form an abutment 12 which is adapted to be engaged by a dynamite cap 13 or other explosive element carried by a head 14 of a relatively strong spring 15.

The spring 15, which is a flat or leaf spring, is secured at its upper end 16 to the body portion of the bracket and is located at the upper portion thereof. The said spring 15 is maintained in a retracted position by a fusible link 17 extending across the spring 15 adjacent the head thereof and passing through apertures at opposite sides of the spring and across the rear face of the body portion. The fusible link is continuous and is adapted to be melted at a relatively low temperature, so that in the event of a fire the heat thereof will release the upper spring arm or member 15. When the upper spring arm or member 15 is released it carries the dynamite cap 13 into contact with the abutment portion 12 of the head 10 and explodes the cap, and practically simultaneously throws the head 10 into violent contact with the glass container and smashes the same, thereby releasing the

100

liquid and causing the container and the contents thereof to fall from the supporting bracket. The device will thereby not only awaken any occupants of the premises, but will also extinguish a fire.

5 While a glass container is illustrated in the accompanying drawings, a frangible container of any suitable material may, of course, be employed, and any form of explosive element may be employed which will be exploded with a loud noise by concussion with the abutment portion of the head of the lower spring or container-shattering member 9.

What is claimed is:

15 1. A combined fire extinguisher and alarm comprising a bracket, a frangible container supported by the bracket and adapted to contain a fire extinguishing liquid, a movable container-shattering member mounted 20 on the bracket and arranged to engage and shatter the frangible container, a spring also mounted on the bracket and provided with means for carrying an explosive into contact with the shattering member, means 25 for normally restraining the spring to maintain the explosive carrying means of the spring normally out of contact with the shattering member and releasable for operation under the influence of heat to release 30 the spring to fire the said explosive and actuate the shattering member to shatter the said container.

2. A combined fire extinguisher and alarm comprising a bracket, a frangible container 35 supported by the bracket and adapted to contain a fire extinguishing liquid, a movable container-shattering member mounted on the bracket provided with a head normally resting against the container, a spring mounted 40 on the bracket and provided with means for carrying an explosive violently into contact with the head of the shattering member to fire the explosive and actuate the shattering member to shatter the container, and 45 means for normally holding the spring against operation, said means being fusible and releasing the spring for operation as aforesaid when subjected to heat.

3. A combined fire extinguisher and alarm 50 comprising a bracket, a frangible container supported by the bracket and adapted to contain a fire extinguishing liquid, a movable container-shattering member mounted on the bracket and having a head for engaging 55 and shattering the container, said head being provided with a rearwardly projecting abutment portion, a spring mounted upon the bracket and provided with means for holding an explosive, and fusible means for 60 holding the spring normally in inoperative position, said means being fusible under the influence of heat to release the spring so as to carry the explosive violently in contact with the abutment portion of the said head 65 to fire the explosive and actuate the shatter-

ing member to shatter the container.

4. A combined fire extinguisher and alarm comprising a bracket, a frangible container supported by the bracket and adapted to contain a fire extinguishing liquid, a lower 70 leaf spring forming a container-shattering member and connected at its lower end to the bracket and provided at its upper end with a head normally resting against the container, an upper leaf spring connected at its 75 upper end to the bracket and provided at its lower end with a head adapted to receive an explosive and arranged to carry the same into engagement with the head of the shattering member to fire the explosive 80 and actuate the shattering member to shatter the container, and a fusible element connecting the lower portion of the upper spring with the bracket for holding the said upper spring normally in a retracted position and 85 releasing said upper spring when subjected to a certain degree of heat.

In testimony whereof I have hereunto set my hand, this 26th day of June, 1930.
